J. L. DIXON

PROCESS FOR ELECTRIC STEEL FURNACES

Filed May 27, 1916

Joseph L. Dixon ^{Inventor}
by Wilkinson, Gruber & McKinley
Attorneys

UNITED STATES PATENT OFFICE.

JOSEPH LAWTON DIXON, OF DETROIT, MICHIGAN.

PROCESS FOR ELECTRIC STEEL FURNACES.

Application filed May 27, 1916. Serial No. 160,177.

To all whom it may concern:

Be it known that I, JOSEPH L. DIXON, a subject of the King of England, residing at Detroit, in the State of Michigan, have invented certain new and useful Improvements in Processes for Electric Steel Furnaces; and I do hereby declare the following to be a full, clear, and exact description of the invention, such as will enable others skilled in the art to which it appertains to make and use the same.

Proposals have been made for melting and refining steel and other metals in electric arc furnaces by means of a process in which the metal is melted by means of a long arc at relatively high voltage, and the subsequent refining of the metal carried on while the heating is continued by means of a shorter arc at lower voltage.

20 In the invention which I now disclose I carry out the process in an improved manner which avoids the disadvantages of the process as carried out in previous disclosures.

25 Previous disclosures have proposed that the shortening of the arc shall be accomplished by merely lowering the electrode thereby causing a larger flow of current, which larger current excites a reactance, which in turn automatically causes a decrease in the voltage applied to the electrode. In that case the lowering of the voltage is accomplished at the expense of an undesirable lowering of the power factor. Still 25 further the voltage at the electrode has largely different values for relatively slightly different values of the current. There is a serious disadvantage for the following reasons:

40 Although the power supply to the furnace during refining is in general less than that during melting, yet the power requirements during refining are far from being constant, and in general great variations are necessary during the refining of a single heat.

The necessary variation in the power supply must be obtained by raising or lowering the electrode, which movements, respectively, cause a decrease and an increase in the current. The alteration in the current is accompanied by a very large alteration of the voltage in the opposite direction. Therefore any attempt to adjust the power supply by raising or lowering the electrode 55 is largely neutralized by the opposing variations of the current and of the voltage. It

follows that a relatively small variation in the power supply can be accomplished only by a relatively large lengthening or shortening of the arc. As a result it is found impossible to conduct the refining and satisfy the demands of each movement as regards power supply without having an undesirably long arc during part of the period of refining. In this way the objects of the process are to a large extent defeated.

In my invention I carry out the process in a manner such that the voltage is substantially independent of the current flow, and also such that the voltage may be lowered without lowering the power factor.

To accomplish this, I supply the electric power to the furnace through a transformer, the windings of which are so arranged that the ratio between the primary and secondary voltages may be varied independently of the electrical load taken from the transformer.

The drawing is a diagrammatic illustration of the apparatus I provide for carrying out my invention.

In the drawing, *a* is an electric furnace, *b* is an electrode which may be raised or lowered; *c* and *c* are conductors by which the electric power is conveyed to the furnace, *d* is a transformer having a primary and secondary winding *d'* and *d''*, respectively; *e'* and *e''* are switches by means of which the primary windings of the transformer is connected to the supply mains *f* and *f'* leading from the generating station, not shown. The two switches *e'* and *e''* are connected to the transformer in a manner so that by closing *e'* there are included in the circuit a smaller number of turns of the primary winding than is the case when *e''* is closed. Therefore, when switch *e'* is closed, a relatively high voltage is developed in the secondary winding of the transformer; and when switch *e''* is closed, a relatively low voltage is developed in the secondary winding.

I carry out my improved process as follows:

Switch *e'* is closed, and the electrode is lowered to touch the metal, and then slightly withdrawn, so that an arc is formed between the metal and the electrode. Owing to the relatively high voltage applied to the electrode, the arc is a long one. When the metal is melted, the switch *e'* is opened and then the switch *e''* is closed. The electrode is again lowered until the current begins to

flow. As the voltage applied to the electrode is now lower, the arc between the electrode and the slag, which at this stage is floating on the metal, will be shorter. From this time, until the metal is poured, the supply of heat to the furnace, which of course is the electric power, is adjusted, in accordance with the requirements, by small variations in the position of the electrode. Raising the electrode decreases the current and vice versa. It is important to note that the required movements of the electrode will be small, since the voltage remains substantially constant; and therefore the effect of any alteration of the current, due to an adjustment of the electrode, is not neutralized by a substantial alteration, in the reverse direction, of the voltage. Therefore no substantial alteration in the length of the arc is necessary when varying the power supply.

I claim as my invention:

1. The process of melting and refining steel or other metals which consists in forming an electric arc between a furnace electrode and the metal to melt the latter, subsequently forming between said electrode and the slag over the molten metal a shorter arc with a lower and substantially constant voltage while controlling the power supply 25 during refining by varying the current.

2. The process of refining metal in an electric furnace which consists in carrying out the melting process with a relatively high voltage and a correspondingly long arc and then shortening the arc while lowering the potential to a substantially constant value and while varying the current as is required 35 during the refining process.

In testimony whereof, I have affixed my 40 signature.

JOSEPH LAWTON DIXON.
